UNITED STATES PATENT OFFICE.

THOMAS E. MURRAY, OF NEW YORK, N. Y.

ELECTRIC CUT-OUT.

1,023,826.

Specification of Letters Patent. Patented Apr. 16, 1912.

Application filed November 20, 1911. Serial No. 661,328.

To all whom it may concern:

Be it known that I, THOMAS E. MURRAY, a citizen of the United States, residing at New York, in the county of New York and State of New York, have invented a certain new and useful Improvement in Electric Cut-Outs, of which the following is a specification.

The invention relates to electric out-outs, and is more especially designed for use with heavy currents of, for example, 1000 amperes, or over.

The invention consists in the construction, as hereinafter explained, whereby the contacts and conductors in the device are given large cross sectional area; whereby all of the bridges (whether including fuses or not) between the pairs of fixed contacts, which constitute circuit terminals on the base block, may be connected or disconnected simultaneously with said terminals; whereby each fuse may be separately examined, and whereby passage of the current across the terminals in the block is prevented.

In the accompanying drawings—Figure 1 is a perspective view of my cut-out. Fig. 2 is a transverse vertical section on the line *w*, *w* of Fig. 4. Fig. 3 is a similar section with the bridge containing the fuse removed and a bifurcated metal bridge substituted. Fig. 4 is a horizontal section on the line *y*, *y* of Fig. 2, and Fig. 5 is a side elevation of the modification shown in Fig. 3, with the circuit leads in section.

Similar numbers of reference indicate like parts.

The base 1 is of porcelain or other insulating refractory material, and comprises integrally end walls 2, 3, a longitudinal partition 4, and transverse partitions 5, 6, whereby six recesses are produced, A, B, C, D, E, *f*; three on each side of the block. The middle longitudinal partition 4 extends above the other partitions and end walls, for a purpose hereafter explained. This partition may be made removable and seated in a groove in the base block, as shown in Fig. 3. In each recess are placed two contact plates 7, 8, bent at right angles. The horizontal portions of said plates are secured together

by a screw bolt 9, countersunk on the under side of the base. To said horizontal portions are secured by bolts 10, the terminals of the service conductors 11, 12, 13, 14, 15, 16 of a three-wire system; 11 and 14 being the positive; 12, 15 the neutral, and 13, 16 the negative lead. The vertical portions of each pair of plates 7, 8 are separated by a space.

Resting on the base 1 is a cover plate 17, of porcelain, the ends 18 of which extend beyond the end walls 2, 3, so that said plate can be conveniently handled. On the upper side of said plate is a longitudinal rib 19, having three notches for the reception of the fuse strips, one of which is shown at 20, Figs. 1 and 2. The ends of each fuse strip are connected by bolts 21 to the members of a pair of metal contact plates 21, 23. Each plate is bent in loop form to fit an edge of the cover plate 17, and then the plate is bent again at right angles so as to extend vertically downward to enter the space between the fixed contact plates 7, 8 on the base, which space said plate closely fits.

In the portions of the cover plate which are overlapped by the loops of the plates 22, 23, are made openings, in which are inserted metal rods 24 before the plates 22, 23 are put in place, said rods establishing electrical connection between the arms of said loops. The plates 22, 23 are secured to the cover plate by the bolts 21 which, as already stated, serve to connect the ends of the fuse strip 20 to said plates. When the cover plate 17 is adjusted in place, the vertical portions of plates 22, 23 enter all the spaces between the plates 7, 8, so that the three fuses are thus simultaneously connected in circuit and form parts of the bridges between the members of the pairs of terminals 11, 14, 12, 15 and 13, 16.

Three semicylindrical covers 25, 26, 27, are placed upon the plate 17 and protect the several fuse strips. The end covers 25 and 27 have recesses in their inner walls, and the middle cover 26 recesses in both walls, to receive the rib 19, as shown in dotted lines, Fig. 1. On the base block are fixed standards 28, having openings 29, 30. In order

to secure both the cover plate 17 and the fuse covers 25, 26, 27 in place, a headed rod 31 is passed through the upper openings 29 in standards 28, and secured by a padlock, 5 or other seal device, 32, the shackle of which passes through an aperture near the end of said rod.

The fuses may all be removed simultaneously by taking plate 17 off the base block, 10 and, if desired, bifurcated metal bridges may be substituted, as shown in Figs. 3 and 5. Another plate, 33, similar to plate 17, has a groove on its under side which receives three bifurcated bridge plugs, (one of 15 which is shown at 34, Fig. 3) secured in place by screws, (one shown at 35). Said plugs enter between the plates 7, 8, and bridge the pairs of terminals 11, 14, 12, 15 and 13, 16. In order to secure the plate 33 20 in place, the rod 31 is passed through the lower openings 30 in standards 28, and secured, as already described.

The construction above described is especially devised to afford large areas of 25 conductor in the device, and thus to adapt it for its use with heavy currents. The plates 7, 8 extend upward to the level of the upper surface of the base block. The outer plate of each pair then lies snugly in the angles of 30 the bent plates 22 and 23: thus affording a large area of conductors in close contact. In order to prevent jumping of current between the inner plates of said pairs, the longitudinal partition 4 in the base block is carried 35 above the upper extremities of said plates, and is received in a groove in the under side of slab 17, Fig. 2, or in the loop of the bifurcated plug 34, Fig. 3. The inserted rod 24, extending between the loop arms of 40 plates 22, 23, also increases the conducting area of said plates. The covers 25, 26, 27 may be removed separately, so that any fuse may be examined or replaced without exposing the others.

45 I claim:

1. An electric cut-out, comprising a base block, having a plurality of pairs of recesses, contacts in said recesses, a substantially flat removable cover plate for said block extending over said recesses, a plurality of pairs of contacts depending from said plate and coöperating respectively with the contacts in said recesses, and fuses on the upper side of said plate, the terminals of 55 each fuse being connected to a pair of said depending contacts.

2. An electric cut-out, comprising a base block, having two recesses, contacts in said recesses, a cover plate for said recesses, a 60 pair of contacts on said plate, each member of said pair of contacts being formed with a U-shaped loop receiving an edge of said plate, and a depending projection coöperating with a contact in one of said recesses,

and on the upper side of said plate a fuse 65 having its terminals connected to the upper legs of said loops.

3. An electric cut-out, comprising a base block, having two recesses, contacts in said recesses, a cover plate for said recesses, a 70 pair of contacts on said plate, each member of said pair of contacts being formed with a U-shaped loop receiving an edge of said plate, and a depending projection coöperating with a contact in one of said recesses, on 75 the upper side of said plate a fuse having its terminals connected to the upper legs of said loops, and a connection extending through said cover plate and electrically uniting the arms of said loop. 80

4. An electric cut-out, comprising a base block, having two recesses, contact plates in said recesses extending to the tops thereof, a cover plate for said recesses, a pair of bent contacts on said plate, each of said bent contacts coöperating with a face and the upper edge of one of said recess contact plates, and on the upper side of said cover plate a fuse having its terminals connected to said bent contacts. 85

90 5. An electric cut-out, comprising a base block, a plurality of pairs of contacts thereon, a substantially flat removable cover plate for said block, having a rib on its upper surface, a plurality of fuses on said plate extending over said rib, and pairs of contacts on said plate connected to the fuse terminals and respectively coöperating with said block contacts. 95

100 6. An electric cut-out, comprising a base block, a plurality of pairs of contacts thereon, a removable cover plate for said block, a plurality of fuses on said plate, a cover for each fuse, means for securing said covers to said plate, and pairs of contacts on said plate connected to the fuse terminals and respectively coöperating with said block contacts. 105

110 7. An electric cut-out, comprising a base block, a plurality of pairs of circuit terminals thereon, a removable cover plate for said block having a rib on its upper surface, and on said plate a plurality of U-shaped bridges extending over said rib, each bridge having its arms coöperating with the members of a pair of terminals. 115

120 8. An electric cut-out, comprising a base block, a plurality of pairs of upwardly projecting contacts thereon, a partition of insulating material on said block extending between and above the members of said pairs of contacts, a removable cover plate for said block, and on said plate a plurality of U-shaped bridges receiving said partition between their arms, and each bridge having its 12 arms coöperating with the members of a pair of said upwardly projecting contacts. 12

9. An electric cut-out, comprising a base

block, a plurality of pairs of upwardly projecting contacts thereon, a removable partition of insulating material seated in said block, and extending between and above the 5 members of said pairs of contacts, a removable cover plate for said block, having a channel on its under side receiving said partition, and on said plate a plurality of bifurcated bridges receiving said partition be- tween their arms, and the arms of each 10 bridge coöperating with the members of a pair of said upwardly projecting contacts.

In testimony whereof I have affixed my signature in presence of two witnesses.

THOMAS E. MURRAY.
